[57] CLAIM

The ornamental design for a telephone handset, as shown and described.

DESCRIPTION

FIG. 1 is a front elevational view of a telephone handset showing my new design;

FIG. 2 is a rear elevational view thereof;

FIG. 3 is a left side elevational view thereof, the right side elevational view being a mirror image of the left side elevational view;

FIG. 4 is a top plan view thereof;

FIG. 5 is a bottom plan view thereof; and,

FIG. 6 is a front, right, and bottom perspective view thereof.
